DANIEL CARPENTER.

United States Patent Office.

DANIEL CARPENTER, OF SAN FRANCISCO, CALIFORNIA.

Design No. 3,512, dated June 1, 1869.

DESIGN FOR A BLACK-BOARD BRUSH.

The Schedule referred to in these Letters Patent and making part of the same.

To all whom it may concern:

Be it known that I, DANIEL CARPENTER, of the city and county of San Francisco, State of California, have originated and designed a new Brush for Black-Boards, of which the following is a full, clear, and exact description, reference being had to the accompanying drawings, making part of this specification.

My invention relates to a new and original design for a brush, or wiper, for removing chalk-marks from black-boards. The usual manner of making these brushes, is to cover a square block of wood with cloth, or other material; but this is inconvenient, as the corners of the block will scratch the board, and, as a consequence, soon wear out the corners of the brush.

In my design, I construct the back of the brush of leather, or other flexible substance, and the rubbing-surface of lamb-skin, plush, or other soft and yielding material. I then stuff between the two with hair or wool, in such a manner that the corners will be rounded off toward the back, so as to prevent injuring the surface of the boards.

To more fully illustrate and explain my invention, reference is had to the accompanying drawings, forming a part of this specification, of which—

Figure 1 is a back view.

Figure 2 is a cross section.

Similar letters of reference, in each of the figures, indicate like parts.

A is the back of my black-board brush, or wiper, and is made of sole-leather, or other flexible substance, and has its corners rounded, as shown. This back can be ornamented, if desired.

The rubbing-surface B, is made of lamb-skin, plush, or other soft material, sewed to the back, and a stuffing of hair or wool is placed between the two, in such a manner that the thickest portion will be in the middle of the brush, the thickness decreasing toward the sides and corners.

A strap, C, is attached to the back on each side, which gives a convenient hold for the person using it.

For use in schools, this brush will be of the greatest utility and convenience, for the following reasons:

First, black-boards of even or uneven surfaces can be wiped with it.

Second, when dropped upon the floor, less noise will be made.

Third, it will not become filled with chalk, like the common brush, on account of its being soft and elastic.

These reasons, when united to those above stated, as to its utility, durability and convenience, make it far preferable to any other black-board brush.

Having thus described my invention,

What I claim, and desire to secure by Letters Patent, is—

The design for a black-board brush, herein set forth.

In witness whereof, I have hereunto set my hand and seal.

DANIEL CARPENTER. [L. S.]
